UNITED STATES PATENT OFFICE.

WILLIAM D. THOMAS, OF PHILADELPHIA, PENNSYLVANIA.

CARRIER FOR FRAGILE ARTICLES.

1,140,857.

Specification of Letters Patent. Patented May 25, 1915.

Application filed January 31, 1914. Serial No. 815,614.

To all whom it may concern:

Be it known that I, WILLIAM D. THOMAS, a citizen of the United States, and a resident of the city of Philadelphia, county of Philadelphia, State of Pennsylvania, have invented certain new and useful Improvements in Carriers for Fragile Articles, of which the following is a specification.

In transporting fragile articles such as 10 eggs, electric light bulbs, delicate mechanisms, etc., through the mails or otherwise, it is a difficult matter to so pack and support them in the carriers or containers in which they are transported that the jarring 15 and jolting to which they are subjected shall not cause them to break or be otherwise injured. Many attempts have been made to provide carriers for safely transporting such articles but as far as I am aware such attempts have not been successful and failure 20 has been the result.

One of the objects of my invention is to provide a construction of carrier or container in which the most fragile articles may 25 be transported safely without injury from the ordinary jarring, jolting or handling to which they must be subjected in transit through the mails or otherwise. To accomplish this purpose I have provided a construction having means for supporting the 30 articles in what may be described as a hanging position. In other words, I provide a hanging support for the articles to be carried and transported. By supporting the 35 articles in a hanging position in accordance with my invention the said articles are relieved from the violent concussions and jarring effects due, for instance, to dropping the packages containing the said articles. 40 In designing such a carrier applicant has had in mind and it has been his endeavor to produce a carrier of the character in question capable of performing the functions of safety ascribed to it and, therefore, 45 possessing great commercial utility and value.

Other objects and advantages will be referred to in the detailed description of my invention or will be apparent therefrom.

50 In the accompanying drawings I have illustrated one form of a convenient embodiment of my invention, but it will be understood that the same is susceptible of embodiment in other forms and that changes in the 55 details of construction may be made within the scope of the claims without departing

from the principle or from the scope of my invention.

In the drawings: Figure 1 is a view showing in top plan a portion of a container 60 embodying my invention, the lid of the same being open, and also showing a portion of the said container removed thereby exposing an interior part of the carrier; Fig. 2 is a transverse section taken on the 65 line 2—2 of Fig. 1, with the lid of the carrier closed; Fig. 3 is a view similar to Fig. 1 but showing a modified construction of carrier adapted for the transporting of electric light bulbs; Fig. 4 is a transverse section along the line 4—4 of Fig. 3 with the lid of the carrier closed; Fig. 5 is a perspective view showing a detail of construction; and Fig. 6 is a perspective view showing a modified construction of carrier. 70

Referring to the drawings, 1 designates a box, illustrated in the drawings as being substantially rectangular in shape, for receiving the parts of the structure which are adapted to support the articles, such as eggs, 80 electric light bulbs, etc., which are to be transported. It will be understood, of course, that the shape of the package may be changed and that the box or outside covering corresponding to the part 1 may be 85 changed in shape and construction as may be desired or convenient.

In the construction of what may be termed the essential supporting parts of my invention I provide what may be referred to 90 broadly as trays which are of such size and shape that when they are placed together in the manner indicated in the drawings they fill the space within the outside cover or protector 1. The number and size of the 95 trays and consequently the size of the package may be increased as desired so as to carry such greater number of articles in a single package as may be desired, and on the other hand the size of the trays and consequently the size of the package may be diminished if desired. The construction of 100 the trays is substantially identical and a description of one may be regarded as a description of both. 105

Referring now particularly to Figs. 1, 2 and 5 of the drawings, 2, 3, 4, 5 and 6 designate strips of suitable material, preferably card-board, which extend longitudinally of the trays. The strips 2 and 3 and 110 5 and 6 are situated at the outer side edge portions of the trays and are spaced a rela-

tively short distance from each other as is shown in the drawing while the strip 4 is centrally located so as to divide the respective trays into two longitudinal chambers 5 extending substantially the length of the carrier. These longitudinally extending chambers are subdivided into smaller chambers or cells by means of cross-wise or transversely extending strips 7 of the same or 10 similar material. The strips 7 and the longitudinal strips 3, 4 and 5 preferably are interlocked or connected with each other in the manner shown in Fig. 5 of the drawings. The strips 7, having reference to the top 15 tray shown in Fig. 2, are provided with slots 8 in their lower edges, while the longitudinally extending strips 3, 4 and 5 are provided with slots 9 in their top edges so that the strips may be interlocked in the 20 manner shown in Fig. 5. It should be understood that these cells may be formed in any other suitable manner. The top or open side of each of the trays is provided with supporting strips 10 which extend 25 transversely of the tray and are bent so as to extend downwardly into the chambers or cells formed by the strips 3, 4, 5 and 7, and form a part of the support for the articles, such as eggs, to be transported.

30 In the construction as illustrated in Figs. 1, 2 and 5 these strips consist of integral parts of a sheet of corrugated board, or other suitable sheet material, having portions cut out as indicated at 11. These portions are cut out so as to leave an intermediate longitudinal strip 12 and longitudinal side strips 13. The intermediate strip 12 is supported upon the edge of the central longitudinal strip 4 while the side strips of the 35 supporting sheet are supported upon the edges of the strips 2 and 3 and 5 and 6. As already indicated, the portions of the supporting corrugated board intermediate the cut out portions 11 are bent into the chambers or cells formed between the strips 3, 4, 5 and 7 in the manner illustrated in Fig. 2 of the drawings. 15 designates longitudinally extending strips of corrugated board or other suitable sheet material which extend longitudinally of the carrier between the strips 3 and 4 and 4 and 5. These strips 50 15 are bent at intervals so as to cause portions thereof to extend into the chambers or cells formed by the strips 3, 4, 5 and 7 as clearly indicated in Figs. 1 and 2 of the drawings. The strips 15, it will be noted upon reference to Fig. 2, extend underneath the transverse strips 10. The said strips 15 are supported at their opposite 55 ends upon the upper edges of two of the strips 7 and also upon the upper edges of end strips 20 formed by extending the side strips 2 and 6. Intermediate portions of the strips 15 are supported upon the upper 60 edges of intermediate strips 7. It may be

noted that the side and end strips 2, 6 and 20 are held in place in the tray structure by securing the side strips 13 and the opposite end portions of the strips 15 thereto in any suitable manner, as by cementing or pasting 70 the same thereto. It will be noted that the outer parts of the bent portions of the supporting strips 10 and 15 are located inside or within the planes of the outer or bottom edges of the strips 3, 4, 5, 6 and 7 so that 75 said outer parts of said supporting strips do not contact with any support but occupy a hanging relation with respect to the other parts of the structure.

In Figs. 1 and 2 I have shown eggs in 80 place in certain of the compartments formed for the reception of the articles to be transported. It will be apparent from an inspection of the drawings that the articles, for instance, the eggs, are supported entirely 85 by the corrugated strips 10 and 15, and as these strips occupy hanging relation with respect to the other parts of the structure and as they are situated wholly within the outer or bottom edges of the strips 3, 4, 5 90 and 7, it is apparent that such strips cannot contact with any fixed object. The result of this is that the articles carried in the compartments of the container are also prevented from contacting with any fixed object and as a result they are relieved in a large measure from the jarring, jolting and shocks which would otherwise result and by being thus relieved they are prevented from 95 being broken. The ends of the longitudinal 100 strips 3, 4 and 5 project a distance beyond the two outermost transverse strips 7 while the ends of the transverse strips 7 project beyond the longitudinal strips 3 and 5. The presence of the projecting ends of these 105 strips prevents any surrounding member from contacting directly with the longitudinal strips 3 and 5 or the two outermost transverse strips 7. Instead of contacting 110 with the said members 3 and 5 and the outermost strips 7 any surrounding member contacts with the ends of the longitudinal and transverse strips so that a space is left between such surrounding member, whatever it may be, and the said longitudinal members 3 and 5 and the outermost end strips 7. In this manner the articles supported in the chambers or cells are further protected against the effects of jarring, 115 jolting, etc. incident to transporting by mail or otherwise. It is preferable that the articles should fit the cells or nests provided for them with sufficient closeness to prevent any substantial amount of free motion of 120 the articles within the said compartments. It has been found, however, that the spaces in the compartments may be somewhat larger than the articles so as to permit some free motion thereof without any apparent injurious effect. It will be noted that the 125 130 135 140

spaces within the chambers or cells of one tray are complementary to the corresponding spaces in the other tray so that when the two trays are placed together in the manner shown in Fig. 2, with their open sides in contact with each other, chambers or cells are formed for receiving, holding and supporting the articles to be transported.

Referring now to Figs. 3 and 4, in which I have shown a construction adapted for use in the transport of fragile articles of a different shape, such as electric light bulbs, I have provided trays similar to the trays shown in Figs. 1 and 2. The trays in this construction are provided with longitudinal strips 21 and 22 of card-board or other suitable material, and with transverse or cross strips 23 and with end strips 24, the latter being formed integrally with the strips 21, if desired. They may, of course, be formed separately from the strips 21 and secured thereto in any desired manner. The strips 22 and 23 preferably are interlocked with each other in the same manner as the similar strips in Figs. 1 and 2. The transverse strips 23 divide the trays into chambers as indicated in Fig. 3 of the drawings.

For the purpose of supporting the electric light bulbs or similar fragile articles within the compartments, I provide a longitudinally extending supporting strip 27 for supporting the small end 28 of an electric light bulb 29. The opposite end portions of this supporting strip 27 are secured upon the top edges of the strips 24 and the adjoining or adjacent strip 23 while intermediate portions of the said supporting strip 27 are supported upon the top edges of intermediate partition strips 23. The large or bulb portion of the electric light bulb is supported upon or between transverse strips 30 of corrugated or other suitable card-board or equivalent material the opposite ends of which are secured by pasting or otherwise to the top edges of the side members 21 and 22. These supporting strips 30 are bent or flexed as is shown in Fig. 4 of the drawings. Each of the chambers between the strips 23 is provided with one of these transverse supporting strips 30. The trays are each provided also with a longitudinally extending corrugated strip 31 the opposite end portions of which are secured by pasting or otherwise to the top edges of the end strips 24 and the adjacent or adjoining strips 23 while intermediate portions thereof are supported upon the top edges of the intermediate partition strips 23. The strip 31 occupies the opposite side portion of the tray from the strip 27. It should be noted that the bent portions of the strip 27 intermediate the transverse partition strips 23 are located above the transverse strips 30 while the portions of the longitudinally extending strip 31 are lo-

cated below or outside of the said strips 30, as is clearly shown in Fig. 4 of the drawings. It will be noted that when the open sides, or what I have termed the tops, of the trays are placed in contact with each other, as shown in Fig. 4, the small or attaching end of the electric light bulb is held between the confronting strips 27 while the bulb proper is held between the confronting transverse strips 30. By the arrangement as shown the strips 27, 30 and 31 are so positioned with respect to each other that the bulbs are securely held against undue motion in any direction with respect to the carrier or container. The longitudinal supporting strip 31 reinforces the strips 30 so as to reduce to a minimum the possibility of a break-down of the structure while in transit. These strips constitute hanging supports for the bulbs.

In use, the articles to be shipped or transported are placed in the open chambers or cells in one of the trays of the character shown in Figs. 1 and 2 or 3 and 4, after which the other tray is inverted and is placed over the first tray so that the articles, whether eggs, electric light bulbs, or any other fragile articles, are completely inclosed within the closed chambers or cells formed by the two trays. As has already been indicated, any desired number of trays may be employed, the sizes of which may be as preferred, so that the sizes of the packages and the number of articles to be transported in a single package may be varied as desired. The assembled trays are then inclosed in a protector or wrapper, such, for instance, as that indicated by the reference numeral 1 in the drawings. If a wrapper or protector, such as is shown in the drawings, is employed, the assembled trays are placed therein after which the lid 35 of the same is closed, its outer free edge 36 being inserted between one side of one of the trays and one side of the wrapper or protector, as is shown in Figs. 2 and 4 of the drawing. Any means may be employed for retaining the cover or lid of the wrapper or protector in closed position.

In the modified structure shown in Fig. 6 the trays 40 and 41 are of the same construction as the trays shown in Figs. 1, 2 and 5 except that the side strips 2 and 6 and the end strips 20 are omitted so that the opposite ends of the transversely extending partition strips 7 and of the longitudinally extending strips 3, 4 and 5 are in contact with the interior surface of the wrapper or protector 1 or the equivalent thereof in which the trays are placed for shipment.

I claim:

1. In a carrier for fragile articles, the combination of coöperating complementary members each consisting of longitudinally and transversely extending strips spaced so

as to form chambers and flexible strips having flexed portions which project into the said chambers and which flexible strips are supported from the edges of said longitudinally and transversely extending strips and constitute hanging supports for articles to be transported in said carrier.

2. In a carrier for fragile articles, the combination of coöperating complemental members each consisting of interlocked longitudinally and transversely extending strips spaced so as to form chambers and flexible strips situated in the said chambers and supported from the edges of said longitudinally and transversely extending strips and constituting hanging supports for articles to be transported in said carrier, and means for retaining and holding the said coöperating members with their tops in operative contact with each other forming cells for receiving and supporting fragile articles.

3. In a carrier for fragile articles, the combination of complemental trays arranged with their open tops in contact with each other and each of the said trays being provided with a plurality of transversely and longitudinally extending strips which divide the said trays into chambers and flexed transversely and longitudinally extending strips which project into the said chambers, the said last mentioned strips in one tray coöperating with those in another tray to support articles placed therein.

35 4. In a carrier for fragile articles, the combination of complemental trays arranged with their open tops in contact with each other and each of the said trays being provided with a plurality of interlocking

transversely and longitudinally extending strips which divide the said trays into chambers, flexed transversely and longitudinally extending strips which have flexed portions projecting into the said chambers, the flexed portions of the strips in one tray coöperating with those in the other tray to support articles placed therein, and a protector for protecting and holding the said trays in substantially fixed relation with respect to each other.

5. In a carrier for fragile articles, the combination of complemental trays arranged with their open tops in contact with each other, and each of said trays being provided with longitudinally and transversely extending interlocking strips dividing said trays into chambers, and a sheet of flexible material having portions cut out at intervals therein leaving side, end and longitudinal and transverse intermediate strips, the side, end and intermediate longitudinal strips resting upon and being supported by the said interlocking strips, the said transverse strips being flexed and projected into the said chambers, and other longitudinal strips supported upon the transverse interlocking strips and also being flexed and projected into the said chambers substantially as and for the purpose described.

In testimony that I claim the foregoing as my invention, I have hereunto signed my name this 30th day of January, A. D. 1914.

WILLIAM D. THOMAS.

In the presence of—

CYRUS N. ANDERSON,
CARRIE E. KLEINFELDER.
